US00D852906S

(12) **United States Design Patent** (10) **Patent No.:** **US D852,906 S**
(45) **Date of Patent:** **** Jul. 2, 2019**

(54) **FITNESS EQUIPMENT**

(71) Applicant: **Zhejiang Raytheon Technology Co., Ltd.**, Zhejiang (CN)

(72) Inventor: **Xiangjun Zhu**, Zhejiang (CN)

(73) Assignee: **ZHEJIANG RAYTHEON TECHNOLOGY CO., LTD.**, Zhejiang (CN)

(**) Term: **15 Years**

(21) Appl. No.: **29/628,140**

(22) Filed: **Dec. 1, 2017**

(30) **Foreign Application Priority Data**

Jul. 27, 2017 (CN) 2017 3 0337737

(51) **LOC (11) Cl.** **21-02**

(52) **U.S. Cl.**

USPC **D21/676**

(58) **Field of Classification Search**

USPC 482/5, 38, 41, 51, 92, 99, 121, 130, 133, 482/138; 601/23; D21/662, 673, 676, D21/686, 687, 690, 691, 694, 695, 698, D21/797

CPC A63B 22/203; A63B 23/0227; A63B 21/0421
